CLAIM

The ornamental design for a table, as shown and described.

DESCRIPTION

FIG. 1 is a perspective view of a first embodiment of the table of the present design;

FIG. 2 is a front elevation view thereof; the rear elevation view being identical thereto;

FIG. 3 is a right side elevation view thereof; the left side elevation view being identical thereto;

FIG. 4 is a top plan view thereof;

FIG. 5 is bottom plan view thereof;

FIG. 6 is a perspective view of a second embodiment of the table of the present design;

FIG. 7 is a front elevation view thereof; the rear elevation view being identical thereto;

FIG. 8 is a right side elevation view thereof; the left side elevation view being identical thereto;

FIG. 9 is a top plan view thereof;

FIG. 10 is a bottom plan view thereof;

FIG. 11 is a perspective view of a third embodiment of the table of the present design;

FIG. 12 is a front elevation view thereof, the rear elevation view being identical thereto;

FIG. 13 is a right side elevation view thereof; the left side elevation view being identical thereto;

FIG. 14 is a top plan view thereof; and,

FIG. 15 is a bottom plan view thereof.

The broken lines in the drawings illustrate portions of the table that form no part of the claimed design.

1 Claim, 15 Drawing Sheets
